Attorney.

UNITED STATES PATENT OFFICE

HARRY G. HUEBNER, OF PHILADELPHIA, PENNSYLVANIA

MEANS FOR HOLDING NECKTIES

Application filed December 21, 1927. Serial No. 241,506.

The invention relates to improvements in means for holding neckties.

The object is to provide improved means for holding each tie independently and maintaining the same smooth, and also means for associating a number of said ties with their supporting elements in such relationship, that the individual ties may be inspected separately, and so that one or more ties may be withdrawn from the associated group without disturbing the group relationship of the remaining ties, and also so that one or more ties may be introduced into a group without disturbing the group relationship of the others.

15 The invention comprises flat forms or supporting elements, tapering from one end to the other, adapted to be inserted into the broader open end of the tie and to extend a substantial distance into said broader end portion and to fit snugly therein to maintain the surrounding portion of the tie smooth and flat. The invention is especially adapted for use with ties of the type usually known as "four-in-hand".

25 The invention also comprises a container or receptacle for holding in association a group of said ties with their supporting elements so that the same may be manipulated as hereinafter described.

30 This container is preferably provided with means for cooperating with the several supporting elements to hold the same in required relative positions and at the same time to permit the lifting of one or more supporting elements without disturbing their group relationship and to permit removing or inserting one or more of said supporting elements without disturbing the group relationship of the others.

40 Referring to the drawings which illustrate merely by way of example a suitable embodiment of my invention:—

Fig. 1 is a plan view of the box with the lid or cover removed.

45 Fig. 2 is a section on line 2, 2 of Fig. 1, showing the lid or cover in place.

Fig. 3 is a side elevation showing some of the tie-supporting elements elevated at one 50 end.

Fig. 4 is a rear elevation of the tie on its supporting element.

Fig. 5 is a fragmentary section showing the method of removing any supporting element, with its tie, from the box without removing 55 the others.

Fig. 6 is a view in perspective, on a reduced scale, of a three compartment box for showing a plurality of ties simultaneously.

Similar numerals refer to similar parts 60 throughout the several views.

The box 7 may be of any depth for accommodating the desired number of ties 8 with their forms or supporting elements 9. The box, in the example shown, is provided with the 65 lateral oppositely directed projections 10 secured to the side walls of the box and formed in any suitable way. The projections 10 preferably extend from the bottom of the box to the top margin of the side walls, and 70 are spaced a substantial distance from one end wall of the box as shown.

The forms or supporting elements 9 are tapered throughout their greater extension and are rounded at the small end, as at 11. 75 The other end 12 of each supporting element 9 is preferably of substantially rectangular shape having portions or wings projecting beyond the line of the longitudinal side margins of the tapered extension. This rectangular formation is adapted to fit snugly in the compartment 13 formed between the end of the box and the projections 10.

The wider end portion of the tie, which is indicated by the numeral 8 in Fig. 1, is of 85 the usual tubular formation and fits over the tapered form or supporting element 9, which maintains this part of the tie stretched flat and smooth. The remaining portion of the tie is folded behind or beneath the element 90 9 and is secured in any suitable way, as for example by bands or pins. The tapered supporting elements or forms 9 are rounded at the smaller end 11 to facilitate the insertion 95 of the form into the open end of the tie.

Each tie and its supporting element comprise a self-sustaining unit. Each unit may be placed within the box, one upon another, with the enlarged portions 12 of the supporting elements fitting in compartment 13. This 100

arrangement normally maintains the units in definite relationship with the box and with each other, that is, spaced symmetrically with respect to the walls of the container, and where several units are packed together, 5 they are maintained in perfect register one upon another.

When it is desired to inspect any unit, one or more units may be raised, as indicated in 10 Fig. 3, without removing the enlarged ends 12 from compartment 13. Any tie is thus readily accessible for inspection. If it is desired to remove any but the topmost unit, all 15 of the units, above the one desired, are raised to the vertical position as in Fig. 5, including the one to be withdrawn, whereupon it is a simple matter to remove the unit desired and permit the remaining ones to fall back into place.

20 It will be noted that in accordance with the invention it is quite possible to inspect, remove or replace any unit from the box or compartment without mussing or disarranging any other unit or otherwise disturbing the 25 group arrangement in the box.

It is well known that in accordance with the present practice, the ties exposed for sale are folded either separately or two or more together and placed in piles in compartments 30 either in boxes or on the counter, and that in order to inspect any particular tie that lies beneath the top one, it is necessary to disturb the folded and piled arrangement. The ties thus become greatly disarranged and mussed 35 and much time is required to straighten out and rearrange the same after a customer is through with his inspection. It follows obviously that the condition of the ties is not improved by the excessive handling, and under 40 any circumstances it is difficult to keep them smooth and in good and attractive condition.

By the arrangement provided in accordance with the present invention, the ties are maintained perfectly smooth and in excellent 45 condition until sold. They are handled very little except as to the portion at the back of the form, when lifting the ends as described.

When the tie is purchased, it remains on its 50 form, thus preserving the smooth and fresh condition of the tie until used. The ties may be replaced upon their forms or supporting elements and thus kept smooth for a long time, and where a box of ties is purchased the ties may be kept in the box and removed and 55 replaced in any order required. This method of caring for the ties is much better than hanging them upon a rack in accordance with the usual custom, in which case there is nothing to maintain the ties smooth and flat 60 or to protect them from the dust, as is possible with a container and its units in accordance with the invention.

Other means may possibly be employed for 65 movably and removably securing the units in

a container without departing from the spirit of the invention.

The usual cover such as 14 is, of course, provided with the box and the boxes may be made with one, two or more compartments to suit 70 special conditions.

What I claim is:—

1. The combination of a container having oppositely extending projections from the side walls and in spaced relationship with one end of the container, a flat tapering necktie supporting formation having side wings adjacent the broader end thereof adapted to engage with said oppositely extending projections. 75

2. The combination of a container having oppositely extending projections from the side walls and in spaced relationship with one end of the container, a flat tapering necktie supporting formation approximately fitting within said container and having flanking shoulders adjacent the broader end of said formation adapted to fit within the space between the oppositely extending projections and the end of the container. 80

3. The combination of a container having oppositely extending projections from the side walls and in spaced relationship with one end of the container, a plurality of superimposed flat tapering necktie supporting formations having side wings adjacent their broader ends adapted to engage with said oppositely extending projections. 90

4. The combination of a container, a plurality of superimposed tapered necktie supporting formations substantially fitting therein and means for securing normal pivotal relationship between the said formations and the container and for permitting the removal of any of said formations from the container. 100

5. The combination of a container, a plurality of superimposed tapered necktie supporting formations substantially fitting therein and means for disengageably securing the said formations in pivotal relationship with the container. 110

6. The combination with a container of a plurality of superimposed tapered necktie supporting formations, each adapted to fit within a tubular portion of a necktie, means for securing the balance of the necktie in folded relationship with the part upon the supporting formation, and cooperating means associated with said container and formations for normally maintaining the formations in proper relative positions, but permitting the withdrawal and the insertion of a formation, while maintaining the group relationship of the remaining formations. 115

HARRY G. HUEBNER.
